UNITED STATES PATENT OFFICE.

ADOLPH C. RECKER, OF OAKVILLE, AND HERBERT C. CADY, OF WATERBURY, CONNECTICUT, ASSIGNORS TO THE CHASE COMPANIES INC., OF WATERBURY, CONNECTICUT, A CORPORATION.

PUSH-TYPE FLUSH RECEPTACLE FOR ELECTRIC INSTALLATION.

Application filed November 5, 1920. Serial No. 421,918.

To all whom it may concern:

Be it known that we, ADOLPH C. RECKER, a citizen of the United States, residing at Oakville, in the county of Litchfield and State of Connecticut, and HERBERT C. CADY, a citizen of the United States, residing at Waterbury, in the county of New Haven and State of Connecticut, have invented a new and useful Improvement in Push-Type Flush Receptacles for Electric Installation; and we do hereby declare the following, when taken in connection with the accompanying drawings and the characters of reference marked thereon, to be a full, clear, and exact description of the same, and which said drawings constitute part of this application, and represent in—

Fig. 1. A view in front elevation of our improved push-type flush receptacle.

Fig. 2. A reverse view thereof.

Fig. 3. A view thereof in central longitudinal section as installed.

Fig. 4. A detached perspective view of the receptacle-plate.

Fig. 5. A corresponding view of the insulating-block.

Fig. 6. A perspective view of the block, looking from its rear face.

Fig. 7. A detached perspective view of one of the contact-springs.

Fig. 8. A corresponding view of one of the terminal-plates.

Our invention relates to an improved push-type flush receptacle for electric installation, the object being to produce a compact fixture of superior simplicity, fewness of parts, and convenience of installation and attention.

With these ends in view our invention consists in a push-type flush receptacle characterized by having its insulating-block carried by its receptacle-plate. Our invention further consists in certain details of construction as will be hereinafter described and pointed out in the claims.

In carrying out our invention as herein shown, the oblong, rectangular receptacle-plate 9 is provided with a circular opening 10, from opposite points of which two parallel mounting-arms 11 are turned inward-

ly at right angles to the plane of the plate for the reception between them of a circular insulating-block 12 made of porcelain or an equivalent material, and having its outer end or face slightly reduced in diameter to form a narrow shoulder 13 fitting snugly within the said opening 10. A long pin or screw 14 passing through a transverse hole 14^a in the block and through the perforations of the said arms secures the block to the plate, the two forming a unitary structure handled as one piece. Under the construction described, the forward end of the block projects through the plate and is substantially flush with the outer face thereof, as shown in Fig. 1. On opposite sides of its center the block is traversed from front to rear by corresponding parallel service-openings 15 entirely isolated from each other. These openings respectively receive corresponding contact-springs arranged longitudinally therein and each having a spring-contact arm 16 and a mounting-arm 17, the former having by preference a retaining-boss 18, and the latter having an opening 19. These contact-springs are held in place by screws 20 located in suitable counter-sunk holes entering the periphery of the inner end of the block and intersecting the respective chambers 15 aforesaid at right angles thereto, the inner ends of these screws passing through the holes 19 in the mounting-arms 17 of the contact springs and thence into threaded openings 21 in the inwardly-turned arms 22 of two corresponding terminal-plates 23, set into shallow recesses in the inner face or end of the block and having threaded openings 24 for the reception of two binding-screws 25 adjacent to which the plates are formed with upstanding fingers 26 between which the service wires (not shown) pass, and which prevent the same from fouling as the binding screws are turned. The contact-springs are thus held in place by the screws 20 which also hold the terminal-plates in place, the binding-screws being exposed upon the rear end of the face of the block and being separated from each other by a radial rib or web 27 made integral therewith.

The push-plug 28, of any approved construction, is provided with the usual parallel contact-fingers 29 which are respectively entered into the outer ends of the service-passages 15 in the block and engage, as shown in Fig. 3, with the contact-arms 16 of the contact-springs.

As shown, the receptacle-plate 9 is demountably fastened by screws 30 to the lugs of an ordinary loom-box 31, shown as located in a recess 32 in a wall 33 to which the box is secured by brackets 35 or in any approved manner. Under our improvement, the insulating-block, instead of being relatively large and installed within the loom-box, is reduced in size and mounted upon and carried by the receptacle-plate, of which it forms a unitary part, so that the insulating-block is installed with the plate and removed with the same. Moreover, the block, on account of its smallness, gives the maximum amount of room within the loom-box for the service-wires which, without overcrowding the box, may be made long enough to permit the plate and block to be connected with the wires at a point sufficiently away from the wall to afford the greatest convenience.

While we have shown our invention as embodied in a fixture of the single type, that is, a fixture confined to the employment of a single push-plug, it is equally well adapted, as we would have it understood, to be embodied in fixtures permitting the use of two or more plugs.

We claim:

1. A push-type flush receptacle for electric installation, having a receptacle-plate formed with an opening, two oppositely-located mounting-arms extending rearwardly from the edges of the said opening at a

right angle to the plane of the said plate, an insulating-block inserted between the said arms and formed with a transverse hole, and means passing through the said arms and through the said hole for securing the block to the plate in line with the said opening therein.

2. A push-type flush receptacle for electric installation, having two oppositely-located, perforated mounting-arms extending rearwardly from the edges of the said opening at a right angle to the plane of the said plate, an insulating-block inserted between the said arms and formed with a transverse hole registering with the perforations therein, and a pin passing through the said arms and hole for securing the block to the plate in line with the said opening therein.

3. A push-type flush receptacle for electric installation, having two oppositely-located, perforated mounting-arms extending rearwardly from the edges of the said opening at a right angle to the plane of the said plate, an insulating-block inserted between the said arms and formed at its forward end with a shoulder by which it is adapted to be fitted into the said opening from the rear of the plate, and the said block being also formed with a transverse hole; and means passing through the said arms and through the said hole for securing the block to the plate with its shoulder positioned in the said opening therein.

In testimony whereof, we have signed this specification in the presence of two subscribing witnesses.

ADOLPH C. RECKER.
HERBERT C. CADY.
